UNITED STATES PATENT OFFICE.

HERBERT H. GARIS, OF EASTON, PENNSYLVANIA, ASSIGNOR TO J. T. BAKER CHEMICAL COMPANY, OF PHILLIPSBURG, NEW JERSEY, A CORPORATION OF NEW JERSEY.

CARBOY.

Application filed October 16, 1923. Serial No. 668,802.

To all whom it may concern:

Be it known that I, HERBERT H. GARIS, a citizen of the United States, residing at Easton, county of Northampton, and State 5 of Pennsylvania, have invented certain new and useful Improvements in Carboys, fully described and represented in the following specification and the accompanying drawings, forming a part of the same.

10 This invention relates to improvements in carboys.

It is the aim of the present invention to provide a simple, cheap and durable carboy in which vertical and lateral shocks 15 imposed on the liquid-holding receptacle thereof during transportation will be effectively cushioned and danger of breakage thus minimized.

To enable others skilled in the art to understand the invention, a detailed description of a preferred embodiment thereof will now be given in connection with the accompanying drawings, and the novel features of the invention will then be specifically 25 pointed out in the claims.

In the drawings—

Figure 1 is a plan view of the improved carboy, with the cover removed, and

Figure 2 is a section on the line 2—2 of 30 Figure 1, with cover in place.

Referring now to the drawings, the numerals 10, 11 indicate, respectively, the sides and bottom of the carboy, which form part of the housing for the liquid-holding receptacle 12, reinforcements 13 on opposite sides being provided to which handles (not shown) or other means for facilitating handling may be attached, corner pieces 14, of substantially triangular cross-section, 35 also being provided extending from the bottom 11 to the tops of the sides 10, to which the latter are secured. The housing for the liquid-holding receptacle should be properly dimensioned with respect to such receptacle so as to provide sufficient clearance between it and the sides for the insertion of the cushioning means hereafter described.

In order that the liquid-holding receptacle 12 may be efficiently cushioned against 50 vertical and lateral shocks, such receptacle is positioned on a raised platform 15 located on the bottom 11, this platform consisting of one or more boards, the ends of which are positioned on and secured to strips or blocks 55 16 which are in turn secured to the bottom

11. The platform 15 should be formed of wood sufficiently thick to support the receptacle 12 when full of liquid without bending, but not so thick as to deprive it of sufficient elasticity to cushion vertical shocks 60 imposed on the carboy. To cushion the receptacle 12 against lateral shocks, and to also strengthen the housing for the receptacle, there are provided at the corners of such housing a plurality of cleats 1, two such 65 cleats preferably diagonally bridging each corner, one near or flush with the top edge of the sides 10 and another just above the platform 15. These cleats 1 are secured at their ends to the housing sides 10 in any suitable manner, as by screws or nails. For economy of space these cleats must be short and they should also be sufficiently thick to support the receptacle 12 against lateral shocks without 70 danger of breakage of the cleats. To increase the resiliency of such cleats, therefore, without reducing their thickness or otherwise weakening them, uprights 2 are provided located between the cleats 1 and 75 the receptacle 12, and these uprights are of such cross-sectional shape as to reduce to a minimum their area of contact with the cleats, whereby the length of the span between the point of contact of the uprights 80 and the cleat ends is increased over what it would be if the flat surface of the uprights was in contact with the cleats, and the proper resiliency of such cleats is thus obtained. Preferably such uprights are 85 formed as shown in cross-section in Fig. 1, that is, with their cleat-engaging sides of convex form, or with a longitudinal ridge, while their opposite or receptacle-engaging surface may advantageously be shaped to 90 conform to the shape of the receptacle 12. The housing for the receptacle 12 is, as shown in Fig. 2, provided with the usual cover 17, which cover, as well as all the other parts of the carboy, may be secured together in any preferred way, or by screws or nails. The uprights 2 may be conveniently secured to the cleats 1 by nails or otherwise.

It will be understood that various changes 105 may be made in the construction illustrated and described while still retaining the invention defined by the claims.

What is claimed is:

1. In a carboy, the combination with the 110

liquid-holding receptacle and housing thereof, of resilient cleats diagonally bridging the corners of said housing and having their ends supported by the side walls of the latter, and bearing members positioned between said cleats and said receptacle.

2. In a carboy, the combination with the liquid-holding receptacle and housing thereof, of resilient cleats diagonally bridging the corners of said housing and having their ends supported by the side walls of the latter, and bearing members having narrowed cleat-engaging surfaces positioned between said cleats and said receptacle.

3. In a carboy, the combination with the liquid-holding receptacle and housing thereof, of resilient cleats diagonally bridging the corners of said housing and having their ends supported by the side walls of the latter, and uprights having a longitudinal ridge formed on their cleat-engaging sides positioned between said receptacle and cleats.

4. In a carboy, the combination with the liquid-holding receptacle and housing thereof, of resilient cleats diagonally bridging the corners of said housing and having their ends supported by the side walls of the latter, and bearing members having concave receptacle-engaging surfaces and convex cleat-engaging surfaces positioned between said receptacle and cleats.

5. In a carboy, the combination with the liquid-holding receptacle and housing thereof, of resilient cleats diagonally bridging the corners of said housing and having their ends supported by the side walls of the latter, bearing members having narrowed cleat-engaging surfaces positioned between said cleats and said receptacle, and a resilient platform on which said receptacle rests.

In testimony whereof, I have hereunto set my hand.

HERBERT H. GARIS.
